UNITED STATES PATENT OFFICE

JOHN F. GAIL, OF EVANSTON, ILLINOIS, ASSIGNOR TO SIMMONS COMPANY, OF NEW YORK, N. Y., A CORPORATION OF DELAWARE

THREAD-CONTROLLED STOPPING DEVICE FOR SEWING MACHINES

Application filed October 2, 1926. Serial No. 139,048.

This invention relates to thread controlled stopping devices for sewing machines and more particularly to a device for preventing the operation of a sewing machine without a supply of thread.

The objects of the invention are to provide means controlled by the supply of thread or other sewing medium which will automatically stop operation of the sewing machine when the thread is broken, comes to an end, or the supply thereof is exhausted and to provide means of the above described character which will be controlled by the normal tension on the thread. Other objects are to provide means of the above described character which will be simple in construction and operation; to provide such means which will not readily become out of order and consequently inoperative; to provide such means which will require practically no attention whatever on the part of the operator and, in general, to provide an improved device of the class described. Other objects and advantages will become apparent when reference is had to the following specification when considered in connection with the accompanying drawings wherein I have illustrated a selected embodiment of my invention and in which:

Figs. 1 and 2 are end and side elevations respectively of a portion of a sewing machine head showing my improved device applied thereto.

Fig. 3 is an elevation of a clutch control and brake mechanism which may be used for transmitting the driving power to the sewing machine and which is adapted to be controlled by my improved device.

Fig. 4 is an elevation having certain parts broken away to more clearly illustrate construction and corresponds to a portion of Fig. 1.

Fig. 5 is an end elevation of the left end of Fig. 4.

Fig. 6 is a plan, and

Fig. 7 is a section on the line 7—7 of Fig. 4.

Referring now to the drawings, a sewing machine head of conventional type is indicated at 10. The head 10 is provided with the usual reciprocating needle bar 11 to which is secured a needle 12 in any suitable manner.

The mechanism for reciprocating the needle bar 11 forms no part of the present invention, but may be of any suitable construction and therefore need not be specifically described or illustrated.

At the top of the head 10, I mount an electric switch 13 which is included in an electric circuit adapted to supply electric energy to a pair of clutch controlling magnets 14 (Fig. 3.) The clutch mechanism includes a pulley 15, clutch collar 16 and clutch lever 17 which is pivoted at 18 to a stationary part of the machine. The clutch lever 17 is provided with suitable means for engaging the collar 16 to engage or disengage the clutch and is also provided with a pin 19 which is adapted to be engaged by a pivotally mounted arm 20 to hold the clutch in engaged position. A spring 21 connected between the end 22 of the arm 20 and a suitable connecting eye 23 on the supporting frame is adapted to normally hold the arm 20 in engagement with the pin 19. The magnets 14 when energized by an electric current are adapted to pull the arm 20 down through the armature 24 whereby the clutch may be released by suitable spring 25 connected to the lower end 26 of the arm 17. Another electric switch 27 is included in the circuit with the switch 13 and magnets 14 and is arranged to break the circuit as soon as the clutch has been disengaged.

The present invention does not include the above described clutch structure per se and, therefore, will not be more specifically described, but a more complete description of this structure may be had by reference to my co-pending application for Machine for making spiral springs, Serial No. 557,121, filed April 28, 1922.

The switch 13 mounted at the top of the sewing machine head 10 preferably comprises a bracket-frame 30 having an attaching ear 31 adapted to be seated against a portion of the sewing machine head and secured thereto by suitable means such as screws as clearly shown in Fig. 1. A block 32 of insulating material is disposed within the frame between the upper leg 33 and lower leg 34 and is secured by suitable means such as screws 35 to the upwardly extending back 100

portion 36 of the frame. A pair of contact members 37 and 38 are secured to the insulating block 32 in such a manner that they are insulated from each other and in the present instance comprises screws 39—39 and 40—40 respectively which threadedly engage suitable apertures in the block. Provision is made for connecting the respective contact plates to wires of the electric circuit in which the switch is connected and comprises plugs 41 and 42 connected to the plates 37 and 38 respectively. The plugs 41 and 42 project through the back 36 of the bracket frame and into suitable apertures in the block 32. One of the screws 39 or 40, as the case may be, in addition to engaging a threaded aperture in the block, also engages a correspondingly threaded aperture in the plug as best shown in Fig. 7. Each of the plugs is provided with an insulating bushing 43 for preventing contact with the bracket frame which is preferably of metal and therefore capable of conducting electricity. The plugs 41 and 42 are preferably split at their outer ends to render them somewhat springy or compressible so that they may be slightly compressed by means of suitable plug sockets 44 as best shown in Fig. 1, whereby the sockets will be retained on the plugs and will make good contact therewith.

The contact members 37 and 38 are also each provided with an outwardly extending resilient ear 45 and 46 respectively which are adapted to be connected by means of a metal cylinder or collar 47 which is normally maintained below the ears and out of contact therewith. The contact collar 47 is beveled at its upper end so as to facilitate entrance between the ears 45 and 46, and is mounted on a suitable bushing 48 of insulating material fixed on a vertical rod 49. The rod 49 is slidably mounted in suitable bearing apertures 50—50 in the upper and lower legs 33 and 34 of the bracket frame. Retrograde movement of the rod 49 with resulting breakage of the circuit is prevented by friction due to pressure of the ears 45 and 46 upon the cylindric portion of the collar 47. The upper end of the rod 49 is preferably bent over and turned downwardly as best shown in Figs. 4 and 5 to provide a downwardly extending portion 51. It will be apparent that when the rod 49 is moved upwardly a sufficient distance, the metal collar 47 will assume a position between the ears 45 and 46 of the contact plates 37 and 38 respectively and will be effective to establish electrical connection theretwixen.

I prefer to actuate the switch mechanism by means associated with the reciprocating needle bar 11 and controlled by tension on the thread T, which is used as a sewing medium. As best shown in Figs. 4, 5, and 6, I mount a bracket 52 on the top of the needle bar 11 by any suitable means such as inter-engaging

threaded stud and aperture on the bar and in the bracket respectively as shown at 53 in Fig. 4. Between the bracket 52 and the top of the bar 11 is interposed a thread guide 54 which preferably comprises a wire member forming a complete loop or eye as indicated at 55 and a downwardly facing open hook portion 56, said eye and hook being spaced apart as clearly shown in Fig. 6.

The thread used in sewing is guided from the usual supply spindle through the eye 55 and the hook 56. Intermediate the eye and hook, the thread engages one leg 57 of a bell crank lever which is pivotally mounted as indicated at 59 in the bracket 52. The thread engages the leg 57 preferably by passing through a suitable aperture in the end thereof as indicated at 60. After the thread leaves the hook 56, it is threaded through a tension or friction device which tends to maintain the thread under normal tension by preventing the needle from pulling too much thread from the supply spindle on any one stroke whereby the thread would otherwise become loose and would not be under any appreciable tension. Tension on the thread is also partly produced by providing some means for holding against withdrawal of the thread from the supply spindle. In cases where a spool of thread is used and the spool is caused to rotate as the thread is pulled therefrom, this holding means may be applied to prevent too free a rotation of the spool.

The first mentioned friction or tension device comprises an upright bar 61 which is secured to the head by suitable means and is relatively stationary. In the present instance, I prefer to mount the bar 61 so as to provide a certain amount of vertical adjustment and I may conveniently do this by providing its lower end with a slot as indicated at 62, (Fig. 1) through which the screw 63 may be passed into threaded engagement with a portion of the head 10. The screw 63 is adapted to clamp the bar 61 in the desired position of vertical adjustment. The bar 61 is provided at its upper end with an overhanging hook portion 64 which is adapted to maintain a leaf spring member 65 in close proximity to the edge 66 of the bar at its upper end. The leaf spring 65 is secured at its lower end to the bar 61 by suitable means such as a screw 67. The thread passes between the edge 66 of the bar and the opposing face of the leaf spring 65 and is thereby placed under a certain degree of tension as it is drawn therethrough from the supply spindle. Another member 68 is also mounted on the upper end of the reciprocating needle bar by being interposed between the bracket 52 and the said upper end and is provided with an outwardly extending ear 69 which is apertured as at 70 to fit over the bar 61 and so as to be capable of being moved in a ver-

tical direction relative to the bar as the needle bar 11 is reciprocated.

It will be apparent that when the needle bar and needle are moved in a downward direction the thread may be pulled between the bar 61 and spring 65 as much as is necessary. It will also be apparent that the loop 55 and hook 56 are effective to cause the thread to move downwardly between the said bar and spring whereby no large amount of thread need be pulled from the supply spindle at any one stroke of the needle bar and also whereby no large amount of slack thread need be provided to permit the necessary reciprocation of the needle bar. On the up stroke of the needle bar the apertured plate 69 is effective to cause the thread between the bar 61 and spring 65 to also move upwardly with the needle bar.

The normal tension on the thread as it passes through the aperture 60 in the leg 57 of the bell crank 58, is sufficient to maintain the leg 57 in a down position against the pressure of a spring pressed plunger 71 which, together with the spring 72, is mounted in a suitable aperture in the bracket 52 as shown in Fig. 4. It will be apparent that if the supply of thread is exhausted or if the thread breaks at some point before it passes between the bar 61 and spring 65 so that the normal tension on the thread is relieved, the spring 72 and plunger 71 will be effective to raise the leg 57 of the bell crank 58 to a position such as illustrated in dotted lines in Fig. 4. It will be noted the pressure of the leaf spring 65 on the thread against the face 66 of the bar 61 is sufficient to prevent the spring pressed plunger 71 from moving the leg 57 of the bell crank 58 upwardly and pulling the thread between the leaf spring 65 and bar 61 from the needle. The bell crank lever 58 is provided with another leg 73 which, in its normal position, when the leg 57 is held down by the thread, will not engage the downwardly facing end 51 of the rod 49. When permitted to assume its operative position as indicated in dotted lines, when the thread is broken and on its up stroke, the leg 73 will be effective to engage this downwardly facing

end so that it will raise the rod 49 and thereby cause the metal collar 47 to establish electrical contact between the contact plates 37 and 38 as above described. When the switch is thus closed, and a circuit completed, the magnets 14 will be energized and the clutch caused to be disengaged as above described. When it is desired to re-start the machine, the operator pushes down upon the upper end of the rod 49 to disconnect the contacts 45 and 46 so as to break the circuit of the control magnets 14, and subsequently effects engagement of the driving clutch mechanism by means of the hand lever 17.

The device is well adapted for use with sewing machines operated at high speed, for

the reason that even though the adjustment may be such that the leg 73 barely engages the abutment 51 when the thread is broken, the inertia, due to the high speed of reciprocation, is effective to fling the rod 49 and associated parts upwardly with a force amply sufficient to force the contact collar 47 between the contacts 45 and 46. A further reason for which the device is well adapted for use with machines operating at a high speed is that the shape and dimensions of the bell crank 57 are, as best shown in Fig. 4, such that the center of gravity of the bell crank lies substantially in a vertical plane passing through the center of the pivot 59. The bell crank is thereby balanced on its pivot on the needle bar, and hence when the machine operates at high speed, causing the needle bar to reciprocate rapidly, the bell crank will not flutter on its pivot. If the bell crank were permitted to flutter, i. e., if it were unbalanced so that it would oscillate on its pivot, due to inertia resulting from the reciprocation of the needle bar, the leg 73 might possibly accidentally engage the abutment 51 and stop the machine, even though the sewing thread retained its normal tension.

I have thus provided a simple and efficient automatic stop mechanism for sewing machines which stop mechanism is controlled by the tension on the thread, and being of relatively few working parts is not likely to become out of order and inoperative. Practically the only attention that need be given the device is to reset the switch rod 49 and the bell crank 58 when thread is rethreaded through the various guides so that the switch will not be closed on starting of the sewing machine unless the thread again breaks or otherwise loses its normal tension. I am aware that various changes in the construction and arrangement of my improved device may be made without departing from the essence of the invention and I therefore reserve the right to make such changes as fairly fall within the scope of the following claims which should be construed as broadly as possible, consistent with the state of the art.

I claim as my invention:

1. In combination, a sewing machine including a reciprocating needle bar having a needle secured thereto, means for guiding thread to said needle, power means for operating said sewing machine, and thread controlled means for shutting off said power means to stop the operation of the sewing machine and comprising an arm movably mounted on said reciprocating needle bar and having means for engaging the thread before the thread reaches the needle whereby the arm is normally held in inoperative position, means for causing said arm to move into an operative position when the tension on the thread is reduced, and means actuated by engagement with said arm when in said

operative position for shutting off said power operating means.

2. In combination, a sewing machine including a reciprocating needle bar having a needle secured thereto and means for guiding thread under tension to said needle, power driving means for driving said sewing machine, electromagnetic means for disengaging said driving means to stop said sewing machine, an electric circuit including a switch for controlling said electromagnetic means, and means for actuating said switch when the normal tension on the sewing thread is reduced and comprising an arm pivotally mounted on said reciprocating needle bar and having an aperture through which the thread passes on its way to the needle, the normal tension on said thread being sufficient to maintain said arm in an inoperative position, and said arm being adapted to move into an operative position for actuating said switch when said normal tension is reduced.

3. In combination, a sewing machine including a reciprocating needle bar having a sewing needle at one end, an electric switch mounted on said sewing machine adjacent said reciprocating bar, means movably mounted on said bar and controlled by the tension on the sewing thread for actuating said switch and normally held in inoperative position by the thread, and means controlled by said switch for stopping the operation of the sewing machine.

4. In combination, a sewing machine including a reciprocating needle bar having a sewing needle at one end and means for supplying thread under tension to said needle, and an electric switch mounted on the sewing machine adjacent said reciprocating bar, an arm pivotally mounted on said reciprocating bar and having thread engaging means and switch operating means, said arm being normally held in inoperative position by engagement with the thread and being adapted to move to an operative position for actuating said switch when the tension on the thread is reduced a considerable amount, and means controlled by said switch for stopping operation of the sewing machine.

5. The combination of a sewing machine head including a reciprocating needle bar, a two position shifting trip member actuated by the machine in unison with said needle bar, the position of said trip member being controlled by the tension on the sewing medium, a two position switch actuated by the machine through said trip member and means associated with the switch for automatically stopping the machine when the switch is actuated by the machine through said trip member.

6. The combination of a sewing machine head including a reciprocating needle bar, a two position shifting trip member carried by said needle bar, reciprocated in unison there-

with and controlled by the tension on the sewing medium, a two position switch actuated by the machine through said trip member and means associated with the switch for automatically stopping the machine when the switch is actuated by the machine through said trip member.

7. The combination of a sewing machine, an electrically operated mechanism for stopping the machine, and means associated with an actuated part of the sewing machine mechanism so as to be actuated by the movement thereof and controlled by the tension on the sewing medium for controlling an electric circuit for actuating said electrically operated mechanism.

8. In combination, a sewing machine including a reciprocating needle bar having a needle at one end, adapted to effect stitching with thread or the like, power means for operating the sewing machine, means for stopping the operation of the sewing machine by said power means, means carried by the needle bar and controlled by the normal tension on the sewing medium for controlling said stopping means, said thread controlled means comprising a two position bell crank pivotally mounted on said reciprocating needle bar so as to be substantially balanced on its pivot, thereby to prevent fluttering of the bell crank as an incident to reciprocation of the needle bar, said bell crank being normally held in one position by the tension on the sewing medium, and means for shifting said bell crank to its second position so as to be effective to actuate said stopping means when the tension on said sewing medium is reduced.

9. In combination, a sewing machine including a reciprocating needle bar having a needle at one end adapted to effect stitching with thread or the like, power means for operating the sewing machine, means for stopping the operation of the sewing machine by said power means, means carried by the needle bar and controlled by the normal tension on the sewing medium for controlling said stopping means, said controlling means including a member movably mounted on said needle bar, reciprocated in unison therewith and having a portion engaged by the sewing medium for normally holding the controlling means out of operative position, and guiding means for the sewing medium, mounted on said needle bar for causing the portion of the sewing medium which engages said controlling means to also reciprocate in unison with the needle bar and controlling means.

JOHN F. GAIL.
